Primary Examiner—Robert M. Spear

(57) CLAIM

The ornamental design for a sign, as shown.

DESCRIPTION

FIG. 1, is a plan view of the front of a sign, showing my new design.

FIG. 2, is a plan view of the rear of the sign of FIG. 1.

FIG. 3, is a plan view of the bottom side of the sign of FIG. 1, the top side being a mirror image thereof; and,

FIG. 4, is a plan view of the left side of the sign of FIG. 1, the right side being a mirror image thereof.
